SEAT-FRAME.

No. 825,751.

Specification of Letters Patent.

Patented July 10, 1906.

Application filed October 28, 1905. Serial No. 284,913.

To all whom it may concern:

Be it known that we, AUSBORN F. OLD, residing at Montclair, in the county of Essex and State of New Jersey, and EDWARD G. BUDD, residing at Philadelphia, in the county of Philadelphia and State of Pennsylvania, citizens of the United States, have invented a certain new and useful Improvement in Seat-Frames, of which the following is a specification.

The object of the present invention is to provide a seat-frame of the character used, for instance, in seating for railway-cars which shall possess maximum strength and rigidity and which may be readily combined or assembled with a seat mechanism or a part thereof by means of which such mechanism may be guided or supported.

In carrying out the invention we employ the usual seat end or "pan," in which may be formed the guide-groove or other device for supporting or guiding the seat-back in its movement from one facing direction to another. Such seat end or pan may also be provided with connections with the sills or rails, which commonly extend from one side of a car-seat to the other and upon which may be supported the cushion, either stationary or interdependently movable with the seat-back. The seat-frame, to which the present invention is directed, is designed to extend around, cover, and protect this seat end or pan and to project upwardly therefrom in order to receive and support a suitable arm-rest, which may be of wood or metal, as preferred. Said frame is preferably formed from a single integral sheet of steel, which may be readily pressed into the desired configuration, enabling it not only to perform its mechanical function, as herein stated, but also adapting it to receive such ornamentation as may be desired to give a finished and tasteful appearance to the structure as a whole.

The invention is illustrated in the accompanying drawings, in which—

Figure 1 is an end elevation of a seat-frame employing our invention. Fig. 2 is a similar view of the other side of said frame, and Fig. 3 is a cross-section on the line 3 3, Fig. 2.

Referring to the drawings, in which similar letters of reference denote corresponding

parts, A designates the seat end or pan. This is here shown as provided with inwardly-turned upper and lower flanges a a' and corresponding inwardly-turned end flanges a^2 a^3 . Said seat end is also shown as provided with an inwardly-projecting guide-rib B, which may be formed integral with the seat end or secured thereto by any suitable means—such, for instance, as the rivets b. Said seat end is provided with bearing-pieces C, having lips c, adapted to receive the upwardly-projecting webs c' of the connecting-rails c², extending from one seat end to another or from one seat end to a suitable support carried by a car-wall.

D designates the seat-frame, formed, as above indicated, of a single integral sheet of steel and here shown as provided with a central panel D' and horizontal ribs D², serving both for ornamentation and for strengthening. Said frame is further shown as provided with beaded vertical side edges d d' and a similarly-beaded lower edge d³, the extreme edges being inwardly flanged toward the center of the seat. Thus the lower edge flange of the frame is illustrated at d³, the depth of this flange being calculated with respect to the depth of the end plate or pan A, which fits snugly therein, as shown in Fig. 3, although said flange d³ may, if desired, be of greater depth and be turned over the edge of the flange a' to firmly hold the same in position. The inward flanging of said frame at all of its edges gives said frame a finished and massive appearance, and this is accomplished by the simple method of stamping or pressing an integral sheet, as above explained.

The seat end or pan A may be secured to the frame in any suitable manner—as, for instance, by rivets—although if it be desired not to mar the outer surface of said frame adjacent to the seat end the securing means need not necessarily extend entirely through such frame. Above the seat end the frame is preferably curved outwardly, as illustrated in Fig. 3, the upper edge being flanged inward at d⁴, this flange corresponding with the flange d³. Such upper edge is here shown as provided with the arm-rest d⁵, which may be of wood or other material and which is provided with a longitudinal slot or rabbet, into which the upper edge of said seat-frame ex-

tends. If the arm-rest be of wood, the same may be secured in position by means of wood-screws passing through the inwardly-turned flange d^4 and extending into said arm-rest.

5 It is to be understood that we do not limit ourselves to the precise design of the seat-frame herein shown and described, as the same may be departed from within wide limits without sacrificing the advantages of the 10 invention. It is to be remarked, however, that a design is to be preferred which, while lending itself to the ornamentation of the seat-frame, will have the effect of strengthening the same both longitudinally and laterally, contributing in that respect with the in-turned edge flanges above described to the 15 rigidity of the frame as a whole.

Having now described our invention, what we claim as new therein, and desire to secure 20 by Letters Patent, is as follows:

1. The combination with a seat end having a flange at its lower edge, of a frame formed in a single integral sheet extending over said seat end and projecting upwardly above the 25 same, said frame having a flange coacting with said flange on the seat end, substantially as set forth.

2. The combination with a seat end having in-turned flanges, of a frame formed in a single 30 integral sheet and provided with a flange adjacent to its lower edge coacting with the corresponding flange of said seat end, said sheet projecting upwardly beyond said seat end, its upper edge being flanged inwardly in correspondence with the lower edge thereof, substantially as set forth.

3. The combination with a seat end having in-turned flanges, of a frame formed in a single

integral sheet, both side edges and both upper and lower edges being flanged inwardly, the 40 lower edge flange coacting with the corresponding flange of said seat end and the upper edge flange coacting with an arm-rest, substantially as set forth.

4. The combination with a seat end having 45 in-turned edge flanges, and means for supporting and guiding a seat-back and seat-cushion, of a frame formed in a single integral sheet of pressed steel flanged inwardly at its side edges and at its upper and lower edges, 50 the body of said sheet intermediate of said edges being paneled, means for securing said seat end to said frame, and an arm-rest carried by the upper flanged edge of said frame, substantially as set forth.

5. The combination with a seat end having in-turned flanges, of a frame formed in a single integral sheet extending over and protecting said seat end and projecting upwardly above the same, said frame having corresponding 60 flanges, the lower edge flange of said frame coacting with the lower edge flange of said seat end, means for securing said seat end and frame together, and panel-ribs formed on said frame and extending both laterally and longitudinally thereof, substantially as set forth.

This specification signed and witnessed this 29th day of August, 1905.
